UNITED STATES PATENT OFFICE.

JOSEPH A. WELSH, OF DUNKIRK, NEW YORK.

REGULATOR FOR HEATING FURNACES.

Application filed October 6, 1923. Serial No. 666,959.

To all whom it may concern:

Be it known that I, JOSEPH A. WELSH, a citizen of the United States, residing at Dunkirk, in the county of Chautauqua and 5 State of New York, have invented new and useful Improvements in Regulators for Heating Furnaces, of which the following is a specification.

This invention relates to a regulator for 10 heating furnaces, and particularly to a combined check and draft door regulator and boiler refill and pressure relief device governed by the expansion and contraction of the water in the heating system.

15 One object of the invention is to provide a simple, reliable, efficient and inexpensive device of this character which will operate the check draft damper and draft door as occasion may require to maintain a certain 20 temperature and which will allow any excess pressure in the system to escape and also supply any required amount of water to the system when the amount contained therein falls below that required for use.

25 A further object of the invention is to provide a device of the character described embodying simple and effective means whereby the working parts may be adjusted or set for as sensitive an operation as desired and to properly regulate the working 30 actions of the check draft damper and draft door to govern the furnace for maintaining any certain temperature.

35 The invention consists of the features of construction, combination and arrangement of parts hereinafter fully described and claimed, reference being had to the accompanying drawings, in which:

40 Figure 1 is a central vertical longitudinal section through a regulator of the character described embodying my invention.

Figure 2 is a sectional end elevation of the same.

45 Figure 3 is a vertical transverse section on line 3—3 of Figure 1.

Figure 4 is a vertical transverse section on line 4—4 of Figure 1.

50 In carrying my invention into practice, I provide a regulator comprising an upper chamber or compartment 1 and a lower chamber or compartment 2. The upper chamber or compartment 1 comprises a cylindrical wall 3 closed by top and bottom heads 4 and 5, the parts being connected and held assembled by bolts 6 and 7, the latter being adjustable and a lock nut 7' being pro-

vided to hold the same in adjusted position.

The head 4 is provided at one side with a pair of upstanding lugs 8 between which extends a draft control lever 9 pivotally connected with the lugs 8 by a bolt or pin 10. One end 11 of the lever 9 extends beyond the lugs and has connected therewith chains or other motion transmitting connections 12 and 13, while the opposite end 14 of the lever extends through a slotted guide yoke 15 and has connected therewith a controlling weight 16. The chains 12 and 13 are designed, in practice, to be suitably connected respectively with the check draft damper and front draft door of the hot water heating furnace or other heater to which the device is applied, so that upon reverse movements of the lever 9, the draft damper and draft door will be alternately opened and closed, as will be readily understood. The slotted guide yoke 15 is cast integrally with the head 4, and is disposed diametrically opposite the lugs 8 to properly guide the lever 9 in its movement. The weight 16 is provided for moving the lever arm 14 downwardly and is adjustably connected therewith, said arm being provided with a series of openings 17 with any one of which the weight 16 may be pivotally engaged by a pin or bolt 18, whereby the weight may be disposed to govern the resistance of the lever to movement under its controlling diaphragm as hereinafter fully described.

95 Disposed within the compartment 3 is a fluid pressure controlled diaphragm 19, comprising a hollow body made of spring metal or other suitable material closed at top and bottom and having corrugated sides whereby it is adapted to expand and contract, accordion fashion. This diaphragm is clamped at its base by a threaded bushing 20 to the bottom head 5 of the casing 1 and has pressed or otherwise fastened to its top wall, a contact member 21 movable through an opening 22 in the head 4 and having a pointed or wedge-shaped end engaging the arm 14 of the lever 9 adjacent to its pivotal connection 10, whereby when the diaphragm 19 expands, the arm 14 of the lever 9 will be raised and its arm 11 depressed and whereby when the diaphragm 19 contracts, the weight 16 will draw the arm 14 of the lever 9 downwardly and elevate the lever arm 11, through which operation the chains 12 and 13 are pulled down or up for the purpose of 100 105 110

opening and closing the check draft damper and front draft door connected therewith.

The bolt 7 has its upper end extending into the base of the slotted guide yoke 15 so as to form an adjustable lower stop for the lever arm 14 and a screw 24 is threaded through the top of the yoke 15 and forms an adjustable stop to limit the upward movement of the lever arm 14, a jamb nut 25 being provided to lock said screw 24 in adjusted position. By means of these stops the movements of the lever 9 may be positively arrested at regulated points to prevent strain upon the working parts of the apparatus contained in the lower compartment or casing 2.

The bushing 20 provides a fluid supply connection between the chamber 2 and the interior of the diaphragm 19, and also serves as a coupling connection between the bottom wall or head 5 of the upper compartment 1 and the top or head of the lower compartment 2, and a washer 26 and clamping nut 27 may be provided to clamp the headed end of this bushing firmly and securely to the head 5 and to fix the base of the diaphragm 19 thereto firmly against disconnection or displacement. The bushing 20 further serves as a guide for an actuating rod 28 which extends upwardly therethrough and into the diaphragm 19 and is suitably connected with the contact member 21, so that the rod 28 will be raised and lowered with the upper diaphragm wall as said diaphragm expands and contracts.

The casing or compartment 2 is provided with an opening 29 for communication with the boiler or water containing space of the heater, and is preferably open at one side, and provided at its opposite side with a detachable closure head 30 secured thereto by screws or bolts 31 or a screw thread connection. This head 30 serves also as a manifold or valve chamber, being provided at top and bottom with passages 32 and 33, communicating with suitable threaded openings 34 for connection with pipes or conductors. The passage 32 is designed for the discharge from the system of any excess pressure occurring therein under any excessive rise of temperature, while the passage 33 is provided for the supply of water to the boiler or heater for refilling the same in the event that, under certain conditions replenishment of the boiler with water is necessary. These passages 32 and 33 respectively communicate with the chamber or compartment 2 through ports 35 and 36 controlled by valves 37 and 38. These valves are adapted to move inwardly against proper seats formed at the juncture of each passage with its port, and said valves are movable outwardly into their respective passages 32 and 33 to open communication between the same and the chamber or compartment 2. The valves are

alike in construction, each having a guide stem 39 extending outwardly therefrom and slidably in a guide sleeve 40, said sleeve in turn being slidably mounted in an extension bushing or housing 41 threaded or otherwise fitted into the outer side of the head 30. A coiled expansion spring 42 encloses each valve stem between the valve and its guide sleeve 40 and exerts its expansive pressure to normally hold the valve closed. An adjusting screw 43 is fitted in the outer end of each housing 41 and bears against the sleeve 40 and is provided for adjusting said sleeve to set it in proper relation to the valve and for regulating the tension of the spring 42, so that any degree of sensitiveness of connection of the valve may be established and maintained. A jamb nut 44 engages each screw 43 and is provided for locking the same in adjusted position. Each stem 39 is provided with a bore or passage 39', connecting the chamber 32 or 33 with the chamber of the sleeve 40, for permitting passage of air between said chambers in the movements of the valve, and thereby operating to break any vacuum or compression between the end of the valve stem and the interior of the sleeve 40, liable to cause interference with the movements of the valve.

At its lower end the rod 28 is fitted in a guide plug 45 detachably threaded in an opening 46 at the base of the casing, said plug having a chamber 47 beneath its guide opening and rod, to allow any particles of sediment which may pass through the guide opening to be received thereinto and retained without interfering with the movements of the rod. The plug 45 may be removed at proper times for cleansing and to permit any sediment which may have settled in the chamber 2 to be discharged through the opening 46 which thus serves as a sediment discharge passage. Above its guided lower end, the rod 28 is formed with a slot 48, the upper and lower end walls 49 and 50 of which provide contact surfaces. A rocker lever 51 is fulcrumed to the head 30 as at 52 and said lever is provided with an arm 53 extending through the slot 48 and adapted to be engaged on reverse movement of the rod 28 by the said contact surfaces 49 and 50. The rocker lever is also provided with upwardly and downwardly projecting lugs or arms 54 and 55 each carrying an adjustable contact screw 56 adapted to be secured or locked in adjusted position by a jamb nut 57. The contact screws 56 of the respective arms 54 and 55 are disposed in alinement with the valves 37 and 38, and are arranged for contact therewith, so that on reverse movement of the rocker lever 51 the ports 35 and 36 will be respectively and alternately opened and closed. An opening 58 is preferably formed in the wall of the casing 2 opposite the rocker lever and its

contact screws and is normally closed by a plug or cap 59, upon removal of which convenient access may be obtained to the interior of the casing to permit adjustment of the contact screws and their jamb nuts, as may be required to regulate the action of the valve actuating members on the valves enabling any degrees of sensitiveness of action to be obtained. It will be observed that the valves, rocker lever and all parts of the valve actuating mechanism are mounted upon the head 30, so as to be applied and removed therewith as a unit allowing access and convenient assemblage or disassemblage of the parts for cleansing, repairing or the like.

In the operation of the device it will be understood that the position of the parts may be such that the check damper will be normally closed and the draft door normally opened, or these parts partially opened, for the purpose of governing the draft to maintain as far as possible, the combustion of the fuel in the furnace so as to keep the building in which the heater is arranged at a certain normal temperature. When this temperature is exceeded it will be understood that the diaphragm 19 will be expanded under heat and pressure and will raise the lever arm 14 and lower the lever arm 11 to partially or wholly close the front draft door or partially or wholly open the check draft damper, the extent of opening and closing movement of the door and damper being governed by the degree of temperature above the normal. If this temperature should rise to a very high degree, the diaphragm 19 will be elevated to a maximum extent and the lever 14 also moved to raise its arm 14 and lower its arm 11 to a maximum extent, thus fully opening the check damper and fully closing the draft door to cut off the draft to a maximum degree. At the same time the contact 50 of the rod 28 will be elevated to such a degree that it will engage the arm 53 of rocker lever 51 and move said lever in the direction to cause the contact carried by arm 54 to open the valve 37 and thus allow the excess pressure to vent through the opening 35 and passage 32. When the furnace cools down the parts will be restored to normal position in an obvious manner. In the event that through any cause, sufficient heat cannot be generated in the boiler to produce normal pressure and the pressure falls below the normal, due to the lowering or contraction of the water contents of the boiler below normal, then the diaphragm 19 will collapse to a maximum degree as a result of which lever 9 will be operated to close the check damper and open the draft damper and at the same time the contact surface 49 of the rod 28 will engage the arm 53 of rocker lever 51 and

move said rocker lever in the direction reverse to that previously described, causing the contact of arm 55 to engage and open the valve 38 so as to allow water to enter through the passage 33 and port 36 for flow 70 to the boiler, in order to replenish the same to the required degree. When this is done and the normal pressure and temperature is re-established, the diaphragm 19 will be expanded to the normal extent as a result of 75 which the valve 38 will be closed and the parts restored to normal position shown in Figure 1.

From the foregoing description, taken in connection with the drawings, it will be seen that my invention provides a regulator of the character set forth, and for the purpose described, which is simple in construction, reliable and efficient in action and capable of being installed and maintained in proper working condition at a comparatively low cost, also that the invention provides a device which will not only control the draft in a reliable and efficient manner but which will also allow of the automatic escape of 80 any excess or dangerous pressure and also provide for the replenishment of the boiler with a required quantity of water, when, through any cause, the water in the boiler falls below that required for 85 service use. The construction of the device provided for the purpose also enables access to be conveniently obtained to any working part for convenience in keeping the device cleaned or repairing or replenishing any of its parts when the occasion requires. It may be stated that, when the device is installed, it will permit hot water for domestic purposes to be drawn from the heating system, in which event the system 90 will be replenished with water through passage 34, into chamber 33, and through port 36 into lower compartment 2 and thence into the boiler.

Having thus described my invention, I 110 claim:

1. In a regulator of the character described, a pressure controlled diaphragm, a rod actuated by the diaphragm, draft controlling means governed by the rod, fluid supply and pressure relief valves, and a rocker device operatively associated with said rod for actuating said valves on reverse movements of the rod.

2. In a regulator of the character described, a pressure controlled diaphragm, a rod actuated by the diaphragm, draft controlling means governed by the rod, spring closed fluid supply and pressure relief valves, and a rocker device operatively associated with said rod for actuating said valves on reverse movements of the rod.

3. In a regulator of the character described, a pressure controlled diaphragm, a rod actuated by the diaphragm, draft con-

trolling means governed by the rod, spring closed fluid supply and pressure relief valves, and a rocker member actuated by the rod and provided with adjustable contacts for selectively actuating said valves.

4. In a regulator of the character described, a pressure controlled diaphragm, a rod actuated by the diaphragm, draft controlling means governed by the rod, spring closed fluid supply and pressure relief valves, adjusting means for regulating the pressures of said springs, and a rocker member actuated by the rod for opening said valves on reverse movements of said rod.

15 5. In a regulator of the character described, a pressure controlled diaphragm, a rod actuated by the diaphragm, draft controlling means governed by the rod, spring closed fluid supply and pressure relief valves, adjusting means for regulating the pressures of said springs, a rocker member actuated by the rod, and adjustable contacts on said rocker member for selectively engaging and opening the valves.

25 6. In a regulator of the character described, a pressure controlled diaphragm, a rod actuated by the diaphragm, draft controlling means governed by the rod, fluid supply and pressure relief valves, and a rocker arm engageable with spaced contacts on the rod for selectively actuating said valves.

35 7. In a regulator of the character described, a pressure controlled diaphragm, a rod actuated by the diaphragm, a pivotally

mounted draft controlling lever governed by the rod, fluid pressure supply and relief valves, a rocker arm engageable with spaced contacts on the rod for selectively actuating said valves, and an adjustable stop for 40 limiting the retractive movement of the lever.

8. In a regulator of the character described, the combination of an upper chamber, a fluid pressure controlled diaphragm 45 in said chamber, a lower chamber in communication with the upper chamber, a rod connected with the diaphragm and movable in said chambers, a draft controlling lever mounted on the upper chamber and governed by the rod, and fluid supply and pressure relief devices in the lower chamber, including valves governed by the rod.

9. In a regulator of the character described, the combination of an upper chamber, a fluid pressure controlled diaphragm in said chamber, a lower chamber in communication with the upper chamber, a rod connected with the diaphragm and movable in said chambers, the said lower chamber being provided with a passage for communication with a boiler and with a fluid pressure inlet and a fluid pressure outlet, a draft controlling lever mounted on the upper chamber and governed by the rod, and 65 valves controlling said fluid pressure inlet and outlet and governed by the rod.

In testimony whereof I affix my signature.

JOSEPH A. WELSH.
